PLASTIC COATED SHEET MATERIAL

Richard A. Mazur, McFarland, Wis., assignor to United States Rubber Company, New York, N.Y., a corporation of New Jersey

Filed Dec. 3, 1965, Ser. No. 45

Term of patent 14 years

(Cl. D87—3)

The figure of the drawing is a plan view of a plastic coated sheet material showing my new design.

A single repeat of the design pattern is enclosed within the rectangle outlined by the broken lines in the drawing.

I claim:

The ornamental design for a plastic coated sheet material, as shown and described.
